UNITED STATES PATENT OFFICE.

JOHN F. O'CONNOR, OF CHICAGO, ILLINOIS, ASSIGNOR, BY MESNE ASSIGNMENTS, TO
W. H. MINER, INC., A CORPORATION OF DELAWARE.

MINE-CAR CONNECTER.

Application filed September 28, 1923. Serial No. 665,312.

This invention relates to improvements in mine car connecters.

One object of the invention is to provide a simple, efficient and inexpensive connecter which is particularly adapted for mine cars of the type most commonly employed, effective to cushion the shocks in both buff and draft.

Another object of the invention is to provide a device of the character described comprising coupling members, engaging resilient loops, wherein the buff and draft shocks are cushioned by the loops, the loops each directly acting as buffing members.

Other objects and advantages of the invention will more clearly appear from the description and claims hereinafter following.

In the drawing forming a part of this specification, Figure 1 is a vertical, longitudinal, sectional view of the adjacent ends of two mine cars, showing my improvements in connection therewith. And Figure 2 is a top plan view of Figure 1.

In said drawing, each mine car is shown as provided with a flooring 10 composed of a plurality of longitudinally arranged heavy boards 11, and a vertical end wall 12. At the opposite ends, each car is also provided with a drawbar 13. Each drawbar is in the form of an elongated flat plate extending through the end wall 12 and secured to the inner end of the flooring 10. A bolt 14 extending through the drawbar, the outer end of the flooring 10 and a transversely extending reinforcing member 15 at the under side of the flooring, is preferably provided to fix the outer end of the drawbar to the car.

The improved connecter, as shown, comprises broadly, two loop shaped spring members A—A and two coupling elements B—B. In carrying out my invention, I provide a spring member A at each end of the car, the same functioning as a buffer. The buffers A are of like construction, each being in the form of a U shaped loop of bar spring steel, having an outer curved section 16 of relatively long radius and straight side sections or arms 17—17 by which the loop is secured to the corresponding end of the car. Each arm 17 of each loop is fixed to adjacent floor boards 11, between which the same extends by a pair of pins 18—18

extending therethrough and anchored in the respective floor boards.

The coupling elements B—B are of like construction, one being connected to each end of the car. Each coupling element B comprises a straight cylindrical shank 19 having a downwardly bent portion at one end forming a hook 20 by which it is attached to the corresponding drawbar 13, the drawbar being provided with an opening 21 through which the hook extends. The end of hook 20 is bent at right angles as clearly shown in Figure 1, thereby providing a horizontal extension 22 coacting with the under surface of the drawbar to prevent accidental disengagement of the hook. As clearly shown in the drawing, there is sufficient clearance between the extension 22 and the under surface of the corresponding drawbar, and the hook 20 has sufficient play within the opening 21 of the drawbar to permit the element B to be swung vertically. It will be evident that the element B is thus swiveled for movement in both horizontal and vertical planes. Each coupling element is normally so disposed that the shank 19 thereof lies in a horizontal position.

Each of the elements B at the opposite or free end of the shank 19, has formed integral therewith a relatively long coupling pin 23 and a relatively short hook 24. The coupling pin 23 extends downwardly from the shank at right angles thereto and the hook 24 is laterally offset with reference to the shank and lies in a plane at right angles thereto.

The hook 24 comprises a straight section 25 extending upwardly from the shank 19 in alignment with the pin 23, a horizontal section 26 and a downwardly extending terminal portion 27 parallel to the section 25. When the cars are coupled together, the pins 23 of each coupling element B at the end of each car is adapted to engage within the loop of the buffer A of the element B on the adjacent car, and the opposed elements B are so disposed that the hooks 24 thereof extend in opposite directions, each hook being adapted to engage over the shank 19 of the other element B, the terminal portion 27 and the section 25 of the hook of each coupling element B being so spaced as to accommodate the shank of the other coupling ele-

ment B for longitudinal sliding movement. In uncoupling the cars, the same are brought together so as to provide sufficient play between the parts of the coupling members to permit the same to be swung upwardly disengaging the hooks 24 thereof from the shanks 19 and withdrawing the pins 23 from within the respective loops A.

In a buffing action, it is evident that, as the cars approach each other, the coupling elements B will slide relatively on each other and the spring loops of the buffers A will be brought into a butting relation and compressed, thereby absorbing the buffing shocks. During draft, as the cars are pulled apart, the coupling elements B, being relatively fixed to the respective cars, will also be pulled apart and due to the pins 23 thereof engaging the respective loops A, the latter will be elongated, thereby taking up the shocks.

From the preceding description, considered in connection with the drawing, it will be evident that the arrangement which I have provided consists of very few parts, all of simple and economical construction, and the entire arrangement is such that it may be readily applied to either new cars or old cars in service without any material modification of the usual mine car now employed.

I have herein shown and described what I now consider the preferred manner of carrying out my invention, but the same is merely illustrative, and I contemplate all changes and modifications that come within the scope of the claims appended hereto.

I claim:

1. In a connector for cars, the combination with a pair of relatively slidable coupling elements, having coacting guide means thereon, each of said elements also having means thereon for pivotally connecting the same to the end of a car; of yielding shock absorbing means adapted to be detachably connected to each of said coupling elements to take up the shock during draft, said shock absorbing means also being adapted to absorb the shocks during buff.
2. In a connector for mine cars, the combination with a spring buffer fixed to one end of a car and adapted to coact with a similar buffer of another car; of a coupling element swiveled to means on said first named car, said means being disposed in spaced relation with reference to said buffer and adapted to be detachably connected to the spring buffer of the second named car.
3. In a connector for cars, the combina-

tion with a resilient loop fixed to one end of a car and adapted to coact with a similar loop on another car to absorb buffing shocks; of a coupling element swiveled to the said end of said first named car, said element having a pin thereon adapted to engage within the loop on the second named car, thereby yieldingly connecting said cars.

4. In a device of the character described, the combination of a pair of spring loops fixed respectively to the opposite ends of adjacent cars, said loops coacting to absorb the shocks during buff; of a pair of relatively slidable coupling elements having inter-engaging guide means thereon, each of said elements having a downwardly extending arm at one end thereof and a hook at the opposite end thereof for swivelly connecting the same to one of said adjacent cars, said arm being adapted to engage within the loop on the other car, thereby yieldingly connecting said cars.

5. In mine car construction, the combination with a U-shaped resilient buffer secured to one end of a car and adapted to coact with a similar buffer on an adjacent car; of a drawbar fixed to said end of the car; of a coupling element fixed to said drawbar and adapted to coact with a similar coupling element on said adjacent car; an arm rigid with said element and adapted to detachably engage within the U-shaped buffer on said adjacent car; and a guide hook on said element adapted to detachably engage the shank of the coupling element of said adjacent car to guide the same for relative longitudinal sliding movement during both buff and draft.

6. In a device of the character described, the combination with a pair of resilient buffering members fixed respectively to adjacent mine cars; of coupling means for connecting the buffering member of each car to relatively fixed means spaced from the buffering member on the adjacent car.

7. In a device of the character described, the combination with a pair of loop shaped spring buffers fixed respectively to adjacent cars and adapted to directly coact during buff; of means connected to said cars and to each other and adapted to engage within the respective loops for coupling said cars, whereby said cars are yieldingly connected to absorb the shocks during draft.

In witness that I claim the foregoing I have hereunto subscribed my name this 26th day of September 1923.

JOHN F. O'CONNOR.
